UNITED STATES PATENT OFFICE.

GEORGE S. LEWIS, OF OAK PARK, ILLINOIS, ASSIGNOR TO MEAD CYCLE COMPANY, OF CHICAGO, ILLINOIS, A CORPORATION OF ILLINOIS.

SPROCKET.

1,251,979.

Specification of Letters Patent. Patented Jan. 1, 1918.

Application filed October 27, 1916. Serial No. 128,050.

To all whom it may concern:

Be it known that I, GEORGE S. LEWIS, a citizen of the United States, residing at Oak Park, in the county of Cook and State 5 of Illinois, have invented a new and useful Improvement in Sprockets, of which the following is a specification.

My invention relates more particularly to improvement in the art of manufacturing sprockets forming the front driving-sprockets of bicycle constructions.

My primary objects are to provide a sprocket presenting the desired strength and wearing qualities and which may be manufactured at less cost than sprockets as hitherto manufactured, and which shall be lighter 15 in weight.

Referring to the accompanying drawings, Figures 1 to 5, inclusive, illustrate certain 20 of the steps which may be performed in producing my improved sprocket, Figs. 1, 2 and 5 being face views of the blank from which the sprocket is formed and showing it in different stages of construction, and Figs. 25 3 and 4, sections taken at the lines 3 and 4, respectively, on Figs. 1 and 2 and viewed in the direction of the arrows. Fig. 6 is a face view showing by dotted lines the blank in the stage immediately preceding its 30 finished stage, and by full lines the completed sprocket; and Fig. 7, a section taken at the line 7 on Fig. 6 and viewed in the direction of the arrow.

It may be stated at the outset that it is 35 one of the purposes of the invention, as preferably practised, to form the sprocket from a piece of sheet steel, the grade of steel being that usually employed in the manufacture of sprockets as hitherto constructed. 40 In producing my improved sprocket I preferably use a piece of sheet steel and preferably first blank it to circular shape, by any suitable means, as shown in Figs. 1 and 3, and of a diameter slightly greater than that 45 of the finished sprocket. The blank thus formed is then introduced into a press of any desirable construction for drawing the peripheral portion of the blank to form the offset annular portion 8, and the center of 50 the blank is also drawn to form the central offset portion 9 preferably of the irregular contour shown in Fig. 2, these operations, if desired, being simultaneous. The blank thus offset is then introduced into another 55 press of any suitable construction and parts

of the metal are stamped therefrom to produce the openings shown in Fig. 5. The blank is then inserted into another press to rough out the teeth of the gear, as represented by the dotted lines in Fig. 6; and the 60 teeth then milled or otherwise operated on to cause them to be of the proper size, as indicated at 10.

In the finished sprocket it will be noted that the metal of the sprocket is practically 65 of uniform thickness and that the teeth 10, by reason of being formed in the offset-portion 8, are offset relative to the body-portion of the sprocket, the offset portion 9 being provided in the particular construc- 70 tion illustrated to compensate for the offset 8 when this is desired. The opening 11, adjacent the central opening 12 in the sprocket, is provided to receive the usual driving-pin carried by the one of the cranks of the bi- 75 cycle which would extend adjacent the outer surface of the sprocket when the parts are assembled in a crank-hanger.

The provision of the offset portion 8 of the sprocket is of great importance in that 80 the fact that this part is in a different plane from that in which the part of the sprocket adjacent to this offset part is located, forms an annular rib-portion which adds great 85 strength to the structure and permits the sprocket to be formed of relatively thin metal, and this increased strength is aug-mented by the fact that in operating on the blank, as described, to produce this offset portion 8, the metal at the point where the 90 offsetting takes place is drawn and is there-by hardened.

Another advantage is presented by forming the sprocket-wheel as stated, in that the 95 formation of the offset portion 8 does not produce the hardening of the extreme circumferential portion of the blank and from which the sprocket-teeth are to be formed, and thus the cutting of the teeth is per-formed on relatively soft metal, and this is 100 true whether the teeth be first roughed out and then afterward milled, as explained above, or otherwise finished, or whether they are produced by milling, or the like op-eration, only. Of course, it will be under- 105 stood that if it is desired to harden the teeth, this may be done in any desirable way.

Certain successive operations in produc-ing the sprocket-wheel have been described 110

above, but it will be readily understood that, if desired, the order of the steps may be altered and certain operations consolidated.

It will be understood from the foregoing 5 that a sprocket-wheel constructed in accordance with my invention is not only of light weight, stiff, and presents the desired degree of durability, but may be very readily and economically manufactured.

10. What I claim as new and desire to secure by Letters Patent is—

1. A sheet metal sprocket of substantially uniform thickness throughout its extent having a central hub portion, an outer peripheral portion provided with radially extending teeth lying substantially in the medial plane of the sprocket, and an intermediate body portion, said body portion and hub portion lying in planes offset with respect to the medial plane. 15

20

2. A sprocket of substantially uniform thickness having a central hub portion, a peripheral portion with teeth extending radially therefrom at substantially right angles to the axis of the sprocket, and an intermediate body portion, said body portion and hub portion lying in planes at opposite sides respectively of the plane of said radially extending teeth. 25

3. A sprocket of substantially uniform thickness throughout its extent and having its outer edge portion offset relatively to the plane of the adjacent portion of the body of the sprocket and its central portion offset, said outer edge portion extending in a plane substantially at a right angle to the axis of the sprocket, and containing teeth, extending substantially at a right angle to said axis. 30

GEORGE S. LEWIS.
